UNITED STATES PATENT OFFICE.

JOHN HOUSINGER, JR., OF CHICAGO, ILLINOIS.

SASH LATCH.

Application filed July 14, 1924. Serial No. 725,789.

To all whom it may concern:

Be it known that I, JOHN HOUSINGER, JR., a citizen of the United States, residing at Chicago, in the county of Cook and State 5 of Illinois, have invented a certain new and useful Improvement in Sash Latches, of which the following is a full, clear, concise, and exact description, reference being had to the accompanying drawings, forming a 10 part of this specification.

This invention relates to improvements in sash latches, more particularly sash latches for permitting a limited opening of the window, as for ventilation, and for preventing opening therebeyond and thereby 15 surreptitious entry through the window.

An object of the invention is the provision of a generally improved, simplified and inexpensive device having such cooperation 20 with the sash that it receives a maximum bracing therefrom in its set position, and reduces the leverages of imposition of prying and the like stresses to a minimum.

Further objects are to prevent releasing 25 of the bolt or latch from the outside, and to provide, where desired, for confining the opening of the window permitted by the latch to the upper sash so that said opening will be as remote as possible from such 30 things in the room as might otherwise be reached and withdrawn by an implement through an opening at the bottom.

A still further object is to avoid alteration 35 of the sash and setting and to minimize the difficulty of attachment of the device.

The invention is illustrated in the accompanying drawings, in which:

Fig. 1 is a fragmentary perspective view, 40 partially in section, of the upper and lower sashes of a window showing an embodiment of my invention in connection therewith;

Fig. 2 is a perspective view of the lower sash showing the latching member carried thereby in released position;

Fig. 3 is a detail section through the latching member showing one way of preventing releasing of the latch from the outside;

Fig. 4 is a perspective view of the upper and lower sashes of a window showing another embodiment of the invention; and

Fig. 5 is a similar view of another embodiment.

In Figs. 1 and 2, 5 designates the lower sash and 6 the upper sash of the window. 55 The sashes are shown of the conventional type and are slidable in the window frame

8 in the usual or any preferred manner. The vertical sides or stiles of the frame 8 have the usual or any suitable vertical ways 9 separated into ways for the respective sashes 60 by the usual vertical intermediate rail 10. The window panes of the particular structure shown are designated at 12.

In Figs. 1 and 2, the lower sash latching member comprises a pair of latching arms 65 14 and 15. These latching arms are preferably in the form of flat plates or bars and are hinged at one end upon a pin or pintle 16 as by rolling or wrapping about the pin or pintle to form knuckles 17.

The mounting arm or base plate 18 is also preferably in the form of a flat plate 70 or bar and it is scarf'd at its upper end and the upwardly extending intermediate portion is rolled back at 20 about the intermediate portion of pin 16 between knuckles 17 to hingedly connect it to arms 14 and 15. The base plate 18 is fastened by screws 21 adjacent the frame 8 to the inner surface 75 of sash 5 adjacent its upper edge, with the hinge adjacent the inner corner of said upper edge. The positioning of the hinge allows the latching arms 14 or 15 to lie in generally flat engagement with the upper edge or surface of sash 5 and transversely 80 thereacross when the latch is set.

Mounted upon the upper sash 6 is a stop 90 bracket 24 offset at 25 to overlie the end of the arm 14 or 15 which projects from the adjacent side of sash 5. The stop 24 is secured to the sash 6 as by means of suitable screws 26, and it is so spaced or 95 distanced from the upper edge of sash 5 that the desired opening of the window is permitted, and when the maximum opening is reached the offset end 25 of stop 24 engages the projecting end of the arm 14 or 15, as the case may be (the arm 15 being shown in locking position in Fig. 1), and prevents further opening of the window. 100

The amount of opening usually permitted is such as to permit proper ventilation without permitting surreptitious entry through the opening. When the locking arms 14 and 15 are in nonlocking position, the stop 24 is adapted to travel between the sashes and permit complete or any desired amount of window opening in the usual manner. It should be noted that when the latching arm is set, the upper edge 110 of sash 5 braces substantially the entire length of the arm, the projecting end of

the latching arm, which cooperates with the stop, being relatively short and the leverages of imposition of prying stresses and the like are reduced to a minimum. Thus, 5 latching arms and stop brackets of relatively light weight will provide great strength against unauthorized forcing of the window open beyond the opening at which the stop is brought into action.

10 The outer edge of each arm 14 and 15 is notched or scarfed at 28 and a stop bracket 29 is secured by screws 30 to the inner face of the vertical stile of the frame 8. The stops 24 and 29 may be identical to 15 simplify manufacture, distribution and installation.

10 The vertical position of stop 29 on the frame is such that, when the lower sash is closed, the offset end 32 will lie in the path 20 of swinging movement of the slot 28 in the adjacent latching arm, to permit said arm to be swung down into the position shown in Fig. 1. In such position, the offset end 32 of the stop overlies the shoulder 33 at 25 the lower end of slot 28 and, by cooperation with said shoulder, limits the upward movement of the lower sash. The clearance necessary to permit the latching arm to swing past the stop is relatively slight so that 30 the slight upward movement of the lower sash is therefore preferably insufficient to lift the lower edge of the lower sash above the usual batten provided along the frame and therefore insufficient to create an opening 35 between the lower edge of the lower sash and the frame.

With the parts set as shown, the limited opening of the window is confined to downward movement of the upper sash until 40 the stop 24 engages the projecting arm 15. By swinging the arm 14 out to move the shoulder 33 out of the vertical plane of the offset stop edge 32, the limited opening may be secured at the top or bottom of the window, as desired. In use the latching arm which cooperates with the stop member on 45 the frame is arranged adjacent the frame for proper cooperation with said stop member.

50 For the purpose of adapting the device to sashes of different thicknesses, the latching arm 14 may be of greater length than the latching arm 15, as shown. When used with a sash of lesser thickness, the device 55 is arranged at the left-hand side, for example, of the window, as shown in Fig. 1, and the arm 15 is used to limit the opening of the window, while the arm 14 is used to prevent opening of the lower sash.

60 When used with a sash of greater thickness, the device is arranged at the opposite side of the window so that the arm 15 will cooperate with the frame stop to prevent opening of the lower sash, while the arm 65 14 will be swung into position across the

upper edge of the lower sash to underlie stop 24 and limit opening of the window.

To prevent releasing the lock from the outside by inserting an implement between the upper and lower sashes and swinging 70 the arm 15 or 16 back out of latching position, relatively stiff spring arms 40 are secured to the base plate 18 as by means of the screws 21 and are looped about the knuckle of the device and turned in at their 75 free ends for engagement at 42 with the locking arm 15. The engagement at 42 prevents surreptitious release of the lock from the outside. At the same time, however, the free end of the element 40 is adapted 80 to be conveniently sprung into register with the slot or opening 43, as shown in dotted lines in Fig. 3, whereupon the latching arm may be swung out of latching position over the element 40. 85

In Fig. 4, a single latching arm 45 is provided with slots or scarfs 46 and 47 in its opposite edges. In order to simplify matters the frame 8 and its stop 29 have been omitted from Fig. 4 since they are clearly 90 illustrated in Fig. 1. It, therefore, should be understood that when reference is made hereinafter to the frame and its stop that I refer to them as illustrated in Fig. 1. The cooperation with the stop bracket 24' is substantially as before, and in this case slot or scarf 46 permits swinging the latching arm into position for cooperation with the stop on the frame when the device is arranged 95 at the left-hand side of the window, while the slot 47 provides for similar cooperation with the frame stop when the device is arranged at the right-hand side of the window. This embodiment is particularly adapted 100 for use at either or both sides of the window. 105

In the embodiment shown in Fig. 5, the single latching arm 50 is adapted to be swung into and from latching position upon the upper edge of lower sash 5' for cooperation with the bracket stop 51 on the upper sash 6'. This embodiment, as the preceding one, is adapted for use at either or both sides of the window. All provision for latching the lower sash against raising is, however, eliminated so that the desired window opening may at all times be secured either from the top or from the bottom, as desired. This is a satisfactory embodiment 110 of the invention for use where there is no necessity nor desire to prevent raising of the lower sash and it embodies the strength and operating action of the other embodiments and its simplicity is even more pronounced. 115

In the embodiment shown in Fig. 5, I have shown an alternative form of means 120 for preventing releasing of the latching arm from the outside. It comprises a latch having a laterally turned end 55 and preferably provided with a joint 56 in its shank which permits the head 55 to be swung into posi- 125 130

tion to overlie the arm 50 and thereby hold it against being swung up from latching position from the outside as by the insertion of an implement up between the sashes.

5 Swinging of head 55 out of engagement with arm 50 permits convenient releasing of the lock from the inside. The joint in the shank of the latch is preferably tensioned to prevent its being jarred out of 10 latching position and to make its releasing movement difficult.

I claim:

1. The combination with the upper and lower sashes of a window of a sash latch 15 comprising a pair of flat hingedly joined members, one for attachment to the lower sash with the hinge joint between it and the other member adjacent the inner corner of the upper edge of said lower sash, and 20 the other having latching position flat across the upper edge of said lower sash with its free end projecting beyond the outer corner thereof, and a stop secured to the upper sash for engagement with the projecting 25 end of said member and adapted to travel between the sashes to permit complete or any desired opening of the window when said latter member is in a released position.

2. The combination with the upper and 30 lower sashes of a window of a sash latch comprising a pair of hingedly joined members, one for attachment to the lower sash with the hinge joint between it and the other member adjacent the inner corner of the 35 upper edge of said lower sash, and the other having latching position flat across the upper edge of said lower sash with its free end projecting beyond the outer corner thereof, and a stop secured to the upper sash 40 for engagement with the projecting end of said member and adapted to travel between the sashes to permit complete or any desired opening of the window when said latter member is in released position, said hingedly 45 joined members comprising flat plates hinged upon a common pintle, and said stop comprising a flat plate having its latching edge offset toward the lower sash.

3. The combination with the upper and 50 lower sashes of a window, of a sash latch comprising a stop secured to the inner face of one of the side stiles of the upper sash and adapted to travel between the sashes as same are opened past said stop, and a pair of 55 flat hingedly joined latching bars, one for attachment to the inner face of the upper stile of the lower sash, and the other adapted to be swung into latching position flat upon the upper edge of said stile with its free end projecting into the path of movement of 60 said stop member and to be swung into unlatched position down along the inner face of the upper stile substantially parallel with said first bar.

65 4. The combination with the upper and

lower sashes of a window, of a sash latch comprising, a stop secured to the inner face of one of the side stiles of the upper sash and adapted to travel between the sashes as same are opened past said stop, and a pair of flat hingedly joined latching bars, one for attachment to the inner face of the upper stile of the lower sash and the other adapted to be swung into latching position flat upon the upper surface of said stile with its free 70 end projecting into the path of movement of said stop member and to be swung into unlatched position down along the inner face of the upper stile substantially parallel with the first bar, said stop having its lower end 75 offset for latching engagement with the projecting end of said latching bar, said latching bar being braced from its hingedly anchored end at the outer corner of the upper stile to the projecting end at the opposite 80 corner of said stile by its flat engagement upon the upper surface of said stile.

5. In combination, a window frame, upper and lower window sashes, a stop on the upper sash, a stop on the frame, and a latching arm hinged to the lower sash and adapted to lie across the upper edge thereof into projecting position underlying the stop on the upper sash to limit the opening of said upper sash, said arm having a lateral shoulder adapted to underlie the frame stop to prevent opening of the lower sash.

6. The combination with the upper and lower sashes of a window, of a sash latch 100 comprising a pair of hingedly joined members, one for attachment to the lower sash with the hinge joint between it and the other member adjacent the inner corner of the upper edge of said lower sash and the other having latching position flat across the 105 upper edge of said lower sash with its free end projecting beyond the outer corner thereof, a stop secured to the upper sash for engagement with the projecting end of said member and adapted to travel between the sashes 110 to permit complete or any desired opening of the window when said member is in released position, a window frame, and a stop on said frame, the hinged latching member having a lateral scarfed edge to be swung 115 into locking engagement with the frame stop to prevent opening of the lower sash.

7. In combination, a window frame, upper and lower sashes, latching means on one of said sashes and said frame, and co-operating latching means on said other sash adapted to be moved into engagement with the latching means on said sash and to be moved out of engagement therewith into engagement with the latching means on the said 120 frame.

In witness whereof I hereunto subscribe my name this 10th day of July, 1924.

JOHN HOUSINGER, JR.
